UNITED STATES PATENT OFFICE

NICHOLS COUCH, OF LOS ANGELES, CALIFORNIA.

TROUBLE-LAMP FOR AUTOMOBILES.

1,372,403. Specification of Letters Patent. Patented Mar. 22, 1921.

Application filed January 20, 1920. Serial No. 252,806.

To all whom it may concern:
Be it known that I, Nichols Couch, a citizen of the United States, residing at Los Angeles, in the county of Los Angeles and State of California, have invented a new and useful Trouble-Lamp for Automobiles, of which the following is a specification.

My invention relates to lamps to be used upon automobiles. Automobiles are ordinarily equipped with an electric lamp attached to a cord, which cord is usually stored away in some receptacle on the automobile. This cord, when it is desired to use the lamp, is attached to a socket in the dash or some other suitable location and the lamp is hung over some part of the engine or other part of the machine while work is being performed. Such devices are unhandy to use and are frequently broken or lost.

The principal object of my invention is to provide a trouble lamp which is mounted under the hood of the engine, being permanently attached and adjustable into different positions when it is desired to use the lamp.

Other objects and advantages will be made evident hereinafter from the following description and the drawings.

Referring to the drawings which are for illustrative purposes only,

Figure 1 is a side elevation of the front end of an automobile, a part of the hood being broken away to show a lamp embodying a form of my invention mounted therein.

Fig. 2 is an enlarged side elevation, partly in section, of a lamp embodying a form of my invention.

Fig. 3 is a vertical sectional view on line 40 3—3, Fig. 2, and

Fig. 4 is a diagrammatic plan view of the engine showing the lamp mounted thereabove.

The hood 11 of the automobile is usually made in two parts which are hinged as indicated at 12 to a rod or pintle 13 which is supported in any suitable manner in the automobile. 14 designates a bracket or hanger having a recess 15 formed in the top thereof to receive the pintle 13, a set screw 16 being provided which engages the pintle and fixes the hanger thereon.

The under or lower face 17 of the bracket 14 is provided with a groove 18 which runs longitudinally with respect to the pintle 13,

and seated in such groove 18 is a tube or pipe 20. The tube 20 is resiliently held in the groove 18 by means of a stud or bolt 21 which extends through the tube 20 and is threaded into the bracket 14. Arranged between a loose washer 22, which rests against the tube 20, and a loose washer 23, which rests against the head 24 of the stud 21, is a coiled spring 25.

Threaded into each end of the tube 20 is a screw plug 27 the outer end of which carries an electric bulb 28 over which is fitted a guard 29 having a light opening 30. Each plug 27 is also provided with an electric switch operated by a headed pin 31, it being understood that the plug 27, the switch and other parts of the lamp may be of any suitable form and construction, the construction of such parts not being essentially a part of my invention. The tube 20 is provided with an opening 32 through which extends electric wires 33 connected at their inner ends to the plugs 27 at each end of the tube.

The lamp is used in the following manner:

During ordinary conditions and when the lamp is not required for use the lamp assumes the full line position shown in the drawings, but when it is desired to use the lamp the hood is raised and the lamp swung into the dotted line position shown in Fig. 4 or in any intermediate position, the lamp on either side of the engine being illuminated by operating the switch of such lamp.

It is understood that the tension of the spring 25 is sufficient to hold the lamp in the dotted line position shown in Fig. 4 or in intermediate position, and when the lamp is returned to its original position with the tube 20 in the groove 18 of the hanger, the spring 25 has sufficient pressure to prevent the tube from jumping out of the groove or turning on the hanger.

What I claim is:

1. In combination with the hood pintle of an automobile, a trouble lamp comprising a bracket having a recess to receive the pintle and having a longitudinal groove in its under face, a tube lying in said groove, a stud bolt extending through said tube into said bracket, a spring on said bolt arranged to resiliently hold the tube in said groove, a lamp on each end of said tube, and wires for said lamps extending into said tube.

2. In combination with the hood pintle of

- an automobile, a lamp comprising a bracket secured to said pintle having a groove in its lower face, an arm in said groove, means for resiliently attaching said arm to the bracket, and a lamp on said arm.
3. In combination with the hood pintle of an automobile, a lamp comprising a bracket secured to said pintle having a groove in its lower face, an arm in said groove, a bolt extending through said arm into said bracket, a coiled spring on said bolt for resiliently holding the arm in said groove, and a lamp on said arm.
4. In combination with the hood pintle of an automobile, a lamp comprising a bracket secured to said pintle, a tube mounted on 15 said bracket arranged to normally lie longitudinally of said pintle, means for resiliently holding said tube against movement on said bracket, a lamp in each end of said bracket, and a switch for each lamp. 20

In testimony whereof I have hereunto set my hand at Los Angeles, California, this 14th day of January, 1920.

NICHOLS COUCH.
